UNITED STATES PATENT OFFICE.

CLARENCE EUGENE JACK, OF LOUVIERS, COLORADO, ASSIGNOR TO E. I. DU PONT DE NEMOURS POWDER COMPANY, OF WILMINGTON, DELAWARE, A CORPORATION OF NEW JERSEY.

CARTRIDGE-LOADING MACHINE.

1,229,467.

Specification of Letters Patent. Patented June 12, 1917.

Application filed May 22, 1915. Serial No. 29,737.

To all whom it may concern:

Be it known that I, CLARENCE EUGENE JACK, of Louviers, in the county of Douglas, and in the State of Colorado, have invented 5 a certain new and useful Improvement in Cartridge-Loading Machines, and do hereby declare that the following is a full, clear, and exact description thereof.

My invention relates particularly to an apparatus for loading shells, but it has special 10 reference to the loading of paper shells with dynamite.

My invention is an improvement over the mechanism shown in the patent to W. I. 15 Donaldson, No. 899,592, September 29, 1908.

The object of my invention is to provide an improved mechanism for the upstairs portion of the apparatus, whereby the friction incident to the operation of the Donaldson mechanism in this portion of the apparatus while the tamping operation has been discontinued, is avoided to a large degree. In the reciprocation of the parts of the 20 tamping rods in the upstairs portion of the Donaldson mechanism, and while the tamping operation has been discontinued, there is a large amount of friction which results 25 in wear, and similar disadvantages where a large amount of friction is present.

In the detailed description of my invention hereinafter, I shall describe in detail only the upstairs portion of the mechanism, although the entire mechanism is shown in the drawings, inasmuch as the lower portion 30 of the mechanism is exactly like the lower portion of the mechanism shown in the Donaldson patent above referred to.

While my invention is capable of embodiment in many different forms, for the purpose of illustration, I shall show only one 40 form thereof in the accompanying drawings, in which,

Figure 1 is a vertical section of the upstairs portion of a machine made in accordance with my invention;

Fig. 1^a is a similar view of the downstairs portion of the same;

Fig. 2 is a similar view of the upstairs portion showing the parts in another position;

Fig. 3 is a front elevation partly in section of the same; and

Fig. 4 is a section of one of the valves enlarged.

In the drawings I have shown in the up-

stairs portion of my apparatus a framework 1, having a main driving shaft 2 adapted to be rotated from any suitable source of power. This shaft 2 has on its two ends two eccentrics 3, which are designed to move 60 a pair of connecting rods 4, the upper ends of which are connected to stud shafts 5 carried by a reciprocating crosshead 6. The crosshead 6 is arranged to move up and down in the framework 1 on any suitable 65 guides. In the crosshead 6 there are a plurality of cylinders 7, each of which is provided at its top with an air inlet pipe 8 connected by a flexible hose 9 to an air tank 10. The air tank 10 may be provided with 70 compressed air through a supply pipe 11 having an adjustable reducing valve 12 therein for adjusting the pressure within the tank 10. Within each of the cylinders 7 there is a piston 13 carried by a piston 75 rod 14. These piston rods 14 pass out through packings 15 on the lower ends of the cylinders and through cylinder heads 16. In each of the cylinder heads 16 there is an air vent pipe 17 having a branch 18, provided with a hand valve 19 which is arranged to be normally opened to a small degree. The pipe 17 also has a further branch 20, provided with a check valve 21 for permitting the entry of air into the end 80 of the cylinder 7, but preventing the passage of the air through the branch 20 in the opposite direction. The purpose of the pipe 20 and the check valve 21 is to freely permit the entry of air into the lower end of the 85 cylinder 7, so as not to retard the upward movement of the corresponding rod 14, but to prevent the escape of the air through the valve 21 upon the downward movement of the rod 14, so as to permit the escape of the 90 air upon such downward movement, to be controlled by the pipe 18 and the valve 19, which is maintained in a slightly opened position, so as to permit the gradual escape of the air upon such downward movement. 95 This cushions the piston attached to the rod 14 upon the downward movement in the cylinder 7. At their lower ends the rods 14 have shoulders 22, which are adapted to slide within tubes 23 passing downwardly 100 below the upstairs portion of the machine, so as to effect the tamping of the cartridges by their reciprocation. The rods 14 reciprocate in a guide 24, and the tubes 23 reciprocate in a guide 25. Each of the tubes 110

23 has a vertical slot 26 to receive a dogging pin 27, which is supported for horizontal reciprocation in a bracket 28 carried by the tube 23. Each of the dogging pins 27 is normally forced into the adjacent slot 26 by a spring 29 while a downwardly depending pin 30 holds the dogging pin 29 in place on the bracket 28. The bracket 28 may be clamped to the tube 23 in any suitable manner as by a split ring having clamping ears 31. In the tamping operation, when the rod 14 with the tube 23 has reached the upper end of its path, the dogging pin 27 becomes engaged by a projection 32 on a casting 33 carried by a square shaft 34. At the same time, the end of the bracket 28 becomes engaged with a spring-pressed pawl 35, located on the same casting 33, so that by these operations the dogging pin 27 becomes released from the shoulder 22, thus permitting the rod 14 to reciprocate independently of the tube 23, while at the same time, the tube 23 is maintained at the upper end of its path by engagement with the pawl 35. In order to disengage the pawls 35 from the brackets 28 at the proper time in the operation of the machine, the shaft 34 and the castings 33 located thereon are arranged to be moved horizontally in bearings 36 in the framework 1 by means of air pressure exerted against a piston 37 attached to one end thereof and reciprocating in a cylinder 38 located in the framework 1. Air is applied to the cylinder 38 by an air inlet pipe 39. The movement of the square shaft 34 in the opposite direction is effected by a spring 40 located at the other end of the square shaft 34.

The rods 14 are arranged to gradually rise as the shells of the cartridges become gradually filled during the tamping operation, and during this rising movement they are arranged to be held at any elevation reached at the lower end of a particular reciprocation according to the height of the dynamite contained in the shells. This is accomplished by a series of friction pawls 41, which bear against the rods 14 on one side thereof, said rods being supported on the opposite sides thereof by brackets 42 depending from the crosshead 6. These pawls 41 are pivoted upon a shaft 43 located in brackets 44, also depending from the crosshead 6. Each of the pawls 41 has in its interior, however, a chamber 44^a to receive a spring 45, which is located between one end of the chamber 44^a and a plate 46 located radially of the shaft 43 and projecting into the chamber 44^a. The plate 46 is normally moved in the direction which will result in forcing the pawls 41 in a downward direction against the sides of the rods 14 by a spring 47 which rests against one side of a lever 48 attached to one end of the shaft 43 and the other end of which

rests against an abutment 49 attached to one of the depending brackets 44. The lever 48 has, furthermore, on its end, a roller 50 which is designed to coöperate with a cam lever 51, pivoted at its lower end to the framework 1 and attached at its upper end by a link 52 to a piston rod 53 connected to a piston 54, adapted to reciprocate in a cylinder 55, having an air supply pipe 56. A spring 57 is located within the cylinder 55 so as to normally retract the cam lever 51.

At its upper end the crosshead 6 has an upwardly directed bracket 58, which supports a horizontally reciprocable knocker 59, having at one end an upwardly directed projection 60, and at the other end, a horizontally located piston rod 61 connected to a piston 62 in a cylinder 63, provided with air from a pipe 64. Within the cylinder 63, there is a spring 65 which normally retracts the knocker 59. The knocker 59 has, furthermore, at one side thereof a pin 66 which is designed to be engaged by a spring-pressed catch 67 pivoted to the bracket 58. This spring-pressed catch 67 has a downwardly directed arm 68, which is designed to contact with a stop 69, projecting laterally from the framework 1. The upwardly directed projection 60 is arranged to operate a valve lever 70 supported by the framework 1 and connected to a rotary valve 71. This rotary valve 71 is a three-way valve, and has an inlet pipe 72, an outlet pipe 73, and a vent opening 74. In the interior of the valve, there is a passageway 75, which passes entirely through the same and a branch passageway 76, which passes only part way through the same and connects with the middle of the passageway 75. The pipe 73 branches so as to connect the valve 71 with the pipe 39 and the pipe 56.

In the operation of my invention, it will be assumed that the parts are all in the position in which the tamping operation in the filling of the dynamite shells with dynamite is about to begin. In this position of the parts, the brackets 28 will be in engagement with the pawls 35, the dogging pins 27 being moved out of engagement with the shoulders 22 by contact with the projections 32. At the same time, the friction pawls 41 will rest against the sides of the rods 14. Furthermore, at the same time, the knocker 59 will be in the position shown in Fig. 1 with the pin 66 out of engagement with the catch 67, and the valve 71 will be in a position in which the cylinders 38 and 55 will be vented to the outer air through the vent 74 as shown in Fig. 6. When now the mechanism in the lower part of the apparatus has been moved into such a position as to be ready for the filling and tamping of another series of shells, this being done by operating the handle 511 of the Donaldson patent, above referred to, air

will be admitted to the pipe 64, this pipe being connected with pipe 510 of said patent as shown in Fig. 1^a. This will move the piston 62 forward, thereby moving the 5 knocker 59 to the left until the pin 66 thereon engages with the spring-pressed catch 67. This will take place at the lower end of the path of movement of the cross head 6, the latter being always moved up 10 and down by the connecting rods 4 during the operation of the machine. The upward movement of the crosshead 6 now brings the projection 60 and the knocker 59 into contact with one end of the valve lever 70, thereby shifting the valve so as to move the 15 pipe 73 out of communication with the vent 74, and bring the air supply pipe 72 into communication with the pipe 73. Compressed air is now supplied through the 20 pipes 39 and 56 to the cylinders 38 and 55. The compressed air admitted to the cylinder 38, moves the piston 37 therein in opposition to the spring 40, so as to move the square shaft 34 and its attached castings 25 33 laterally, thus disengaging all of the pawls 35 from the brackets 28 so as to cause the shoulders 22, thereby securely fastening the rods 14 and the tubes 26 together for 30 reciprocation in the tamping of the dynamite in the shells. The air which is admitted to the cylinder 55 from the pipe 56 moves the cam lever 51 forwardly thereby moving the lever 48 so as to bring the plate 35 46 on the shaft 43 into contact with one end of the chamber 44, thereby moving the pawls 41 out of engagement with the sides of the rods 14. The air pressure in the cylinders 7 now forces the tamping rods, including 40 the rods 14 and the tubes 26 downwardly so as to begin the tamping of the dynamite in the shells. When now the crosshead 6 moves downwardly, the arm 68 upon the catch 67 engages the stop 69 so as to release 45 the catch 67 from the pin 66, whereupon the spring 65 in the cylinder 63 moves the knocker 59 to the right so as to bring the projection 60 under the other end of the valve lever 70. The upward movement of 50 the crosshead 6 now causes the projection 60 to contact with said other end of the valve lever 70, thereby moving the valve so as to cut off communication between the pipes 72 and 73, and so as to bring the pipe 55 73 into communication with the outer air through the vent 74. The air in the cylinders 38 and 53 now becomes exhausted. As a consequence, the pawls 35 are moved back into their original position, while the shaft 43 is rotated so as to move the plates 46 out of engagement with the ends of the chambers 44^a, thereby causing the springs 45 to move the friction pawls 41 against the sides of the rods 14. As the dynamite is 60 65 now gradually fed into the shells, the lower

limits of the movement of the tamping rods, including the rods 14 and the tubes 26, are gradually raised, thereby gradually elevating the rods 14 and the tubes 26, and as a consequence the friction pawls 41 hold the 70 rods 14 in such a manner that they cannot in any one reciprocation pass below the lower limit of movement in their previous reciprocation. In this way, the rods 14 are gradually raised by the dynamite in the 75 shells, until the brackets 28 come into engagement with the pawls 35 and until the dogging pins 27 release the shoulders 22 by the engagement of the dogging pins with the projections 32. The rods 14 are now 80 free to move in the tubes 26 during the continued reciprocation of the crosshead 6 without causing the tubes 26 and their connected parts located in the lower part of the apparatus to move in their respective 85 guides. If the said parts were required to move in their guides during the reciprocation of the crosshead 6, there would be a considerable amount of friction with consequent wear of parts, loss of power, etc., all 90 of which is obviated by the apparatus when constructed as described in detail above.

While I have described my invention above in detail, I wish it to be understood that many changes may be made therein 95 without departing from the spirit of my invention as defined by the scope of the appended claims.

I claim:

1. In a cartridge loading machine, tamping means, a cross-head adapted to carry the same, and means for avoiding friction between the cross-head and the tamping means when the tamping means has been thrown out of operation, comprising compressed air operated connections between the cross-head and the tamping means.

2. In a cartridge loading machine, tamping means, a cross-head adapted to carry the same, and means for avoiding friction between the cross-head and the tamping means when the tamping means has been thrown out of operation comprising a cylinder and piston connection between the cross-head and the tamping means.

3. In a cartridge loading machine, tamping means, a cross-head adapted to carry the same, and means for avoiding friction between the cross-head and the tamping means when the tamping means has been thrown out of operation comprising a cylinder and piston connection between the cross-head and the tamping means and compressed air connections for forcing the piston forwardly in the cylinder.

4. In a cartridge loading machine, tamping means, a cross-head adapted to carry the same, having means to maintain the tamping means at any elevation to which it is moved by the explosive being tamped, and

means for avoiding friction between the cross-head and the tamping means when the tamping means has been thrown out of operation, comprising compressed air operated connections between the cross-head and the tamping means.

5 5. In a cartridge loading machine, tamping means, a cross-head adapted to carry the same, having means to maintain the tamping means at any elevation to which it is moved by the explosive being tamped, and means for avoiding friction between the cross-head and the tamping means when the tamping means has been thrown out of operation comprising a cylinder and piston connection between the cross-head and the tamping means.

10 6. In a cartridge loading machine, tamping means, a cross-head adapted to carry the same, having means to maintain the tamping means at any elevation to which it is moved by the explosive being tamped, and means for avoiding friction between the cross-head and the tamping means when the tamping means has been thrown out of operation, comprising a cylinder and piston connection between the cross-head and the tamping means, and compressed air connections for forcing the piston forwardly in the cylinder.

15 7. In a cartridge loading machine, tamping means, a cross-head adapted to carry the same, having means to maintain the tamping means at any elevation to which it is moved by the explosive being tamped, comprising a friction pawl, and means for avoiding friction between the cross-head and the tamping means when the tamping means has been thrown out of operation.

20 8. In a cartridge loading machine, tamping means, a cross-head adapted to carry the same, having means to maintain the tamping means at any elevation to which it is moved by the explosive being tamped, comprising a friction pawl, and means for avoiding friction between the cross-head and the tamping means when the tamping means has been thrown out of operation comprising a cylinder and piston connection between the cross-head and the tamping means.

25 9. In a cartridge loading machine, tamping means, a cross-head adapted to carry the same, having means to maintain the tamping means at any elevation to which it is moved by the explosive being tamped, comprising a friction pawl, and means for avoiding friction between the cross-head and the tamping means when the tamping means has been thrown out of operation, comprising a cylinder and piston connection between the cross-head and the tamping means, and compressed air connections for forcing the piston forwardly in the cylinder.

30 10. In a cartridge loading machine, tamping

means, a cross-head adapted to carry the same, having means to maintain the tamping means at any elevation to which it is moved by the explosive being tamped, comprising a friction pawl pivoted to a pawl releasing shaft, and means for avoiding friction between the cross-head and the tamping means when the tamping means has been thrown out of operation.

35 11. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, and means for avoiding friction between the cross-head and the tamping means when the tamping means has been thrown out of operation comprising a cylinder and piston connection between the cross-head and the tamping means.

40 12. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, and means for avoiding friction between the cross-head and the tamping means when the tamping means has been thrown out of operation comprising a cylinder and piston connection between the cross-head and the tamping means, and compressed air connections for forcing the piston forwardly in the cylinder.

45 13. In a cartridge loading machine, tamping means, a cross-head adapted to carry the same, and means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating.

50 14. In a cartridge loading machine, tamping means, a cross-head adapted to carry the same, and means for avoiding friction between the cross-head and the tamping means when the tamping means has been thrown out of operation comprising a cylinder and piston connection between the cross-head and the tamping means, compressed air connections for forcing the piston forwardly in the cylinder, and means for disconnecting the piston rod from the tamping means and holding the latter stationary when the latter is not operating.

55 15. In a cartridge loading machine, tamping means, a cross-head adapted to carry the same, having means to maintain the tamping means at any elevation to which it

- is moved by the explosive being tamped, and means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating. 5
16. In a cartridge loading machine, tamping means, a cross-head adapted to carry the same, having means to maintain the tamping means at any elevation to which it is moved by the explosive being tamped, and means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating. 10
17. In a cartridge loading machine, tamping means, a cross-head adapted to carry the same, having means to maintain the tamping means at any elevation to which it is moved by the explosive being tamped, comprising a friction pawl, and means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating. 15
18. In a cartridge loading machine, tamping means, a cross-head adapted to carry the same, having means to maintain the tamping means at any elevation to which it is moved by the explosive being tamped, comprising a friction pawl, and means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating. 20
19. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, and means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating. 25
20. In a cartridge loading machine, tamping means, a cross-head adapted to carry the same, having means to maintain the tamping means at any elevation to which it is moved by the explosive being tamped, comprising a friction pawl pivoted to a pawl releasing shaft on which it is pivoted, and means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating. 30
21. In a cartridge loading machine, tamping means, a cross-head adapted to carry the same, and means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating, comprising a bracket on the tamping means, a dogging pin thereon for engaging the piston rod and a pawl for engaging said bracket. 35
22. In a cartridge loading machine, tamping means, a cross-head adapted to carry the same, and means for avoiding friction between the cross-head and the tamping means when the tamping means has been thrown out of operation comprising a cylinder and piston connection between the crosshead and the tamping means, compressed air connections for forcing the piston forwardly in the cylinder, and means for disconnecting the piston rod from the tamping means and holding the latter stationary when the latter is not operating, comprising a bracket on the tamping means, a dogging pin thereon for engaging the piston rod and a pawl for engaging said bracket. 40
23. In a cartridge loading machine, tamping means, a cross-head adapted to carry the same, having means to maintain the tamping means at any elevation to which it is moved by the explosive being tamped, and means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating. 45

the piston rod from the tamping means and holding the latter stationary when the latter is not operating, comprising a bracket on the tamping means, a dogging pin thereon for engaging the piston rod and a pawl for engaging said bracket.

24. In a cartridge loading machine, tamping means, a cross-head adapted to carry the same, having means to maintain the tamping means at any elevation to which it is moved by the explosive being tamped, and means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating, comprising a bracket on the tamping means, a dogging pin thereon for engaging the piston rod and a pawl for engaging said bracket.

25. In a cartridge loading machine, tamping means, a cross-head adapted to carry the same, having means to maintain the tamping means at any elevation to which it is moved by the explosive being tamped, comprising a friction pawl, and means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating, comprising a bracket on the tamping means, a dogging pin thereon for engaging the piston rod and a pawl for engaging said bracket.

26. In a cartridge loading machine, tamping means, a cross-head adapted to carry the same, having means to maintain the tamping means at any elevation to which it is moved by the explosive being tamped, comprising a friction pawl, and means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating, comprising a bracket on the tamping means, a dogging pin thereon for engaging the piston rod and a pawl for engaging said bracket.

27. In a cartridge loading machine, tamping means, a cross-head adapted to carry the

same, having means to maintain the tamping means at any elevation to which it is moved by the explosive being tamped, comprising a friction pawl, a pawl releasing shaft on which it is pivoted, and means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating, comprising a bracket on the tamping means, a dogging pin thereon for engaging the piston rod and a pawl for engaging said bracket.

28. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, and means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating, comprising a bracket on the tamping means, a dogging pin thereon for engaging the piston rod and a pawl for engaging said bracket.

29. In a cartridge loading machine, tamping means, a cross-head adapted to carry the same, having means to maintain the tamping means at any elevation to which it is moved by the explosive being tamped, comprising a friction pawl, means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating, and means coöperating with the cross-head for releasing the friction pawl and the bracket engaging pawl.

30. In a cartridge loading machine, tamping means, a cross-head adapted to carry the same, having means to maintain the tamping means at any elevation to which it is moved by the explosive being tamped, comprising a friction pawl, means for avoiding friction between the cross-head and the tamping means when the tamping means has been thrown out of operation, comprising a cylinder and piston connection between the

cross-head and the tamping means, compressed air connections for forcing the piston forwardly in the cylinder, and means for disconnecting the piston rod from the tamping means and holding the latter stationary when the latter is not operating, and means coöperating with the cross-head for releasing the friction pawl and the bracket engaging pawl.

31. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, means for avoiding friction between the cross-head and the tamping means when the tamping means has been thrown out of operation, comprising a cylinder and piston connection between the cross-head and the tamping means, and means for disconnecting the piston rod from the tamping means and holding the latter stationary when the latter is not operating, and means coöperating with the cross-head for releasing the friction pawl and the bracket engaging pawl.

32. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating, and means coöperating with the cross-head for releasing the friction pawl and the bracket engaging pawl.

33. In a cartridge loading machine, tamping means, a cross-head adapted to carry the same, having means to maintain the tamping means at any elevation to which it is moved by the explosive being tamped, comprising a friction pawl, means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating, comprising the piston rod and a pawl for engaging said bracket, and means coöperating with the cross-head for releasing the friction pawl and the bracket engaging pawl.

34. In a cartridge loading machine, tamping means, a cross-head adapted to carry the same, having means to maintain the tamping means at any elevation to which it is moved by the explosive being tamped, comprising a friction pawl, means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating, comprising a bracket on the tamping means, a dogging pin thereon for engaging the piston rod and a pawl for engaging said bracket, and means coöperating with the cross-head for releasing the friction pawl and the bracket engaging pawl.

35. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, means for avoiding friction between the cross-head and the tamping means when the tamping means has been thrown out of operation comprising a cylinder and piston connection between the cross-head and the tamping means, and means for disconnecting the piston rod from the tamping means and holding the latter stationary when the latter is not operating, comprising a bracket on the tamping means, a dogging pin thereon for engaging the piston rod and a pawl for engaging said bracket, and means coöperating with the cross-head for releasing the friction pawl and the bracket engaging pawl.

36. In a cartridge loading machine tamping means, a cross-head adapted to carry the same, having means to maintain the tamping means at any elevation to which it is moved by the explosive being tamped, comprising a friction pawl, a pawl releasing shaft on which it is pivoted, means for avoiding friction between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating, comprising a bracket on the tamping means, a dogging pin thereon for engaging the piston rod and a pawl for engaging said bracket, and means coöperating with the cross-head for releasing the friction pawl and the bracket engaging pawl.

37. In a cartridge loading machine, tamping means, a cross-head adapted to carry the same, having means to maintain the tamping means at any elevation to which it is moved by the explosive being tamped, comprising a friction pawl, means for avoiding friction between the cross-head and the tamping means when the tamping means has been thrown out of operation comprising 5 a cylinder and piston connection between the cross-head and the tamping means, and means for disconnecting the piston rod from the tamping means and holding the latter stationary when the latter is not operating, and means coöperating with the cross-head for releasing the friction pawl and the bracket engaging pawl, comprising an air cylinder, a knocker connected thereto, a catch for engaging the knocker, a rotary valve adapted to be moved by the knocker and compressed air connections through the valve and to the said pawl releasing devices. 10 15 20 25

38. In a cartridge loading machine, tamping means, a cross-head adapted to carry the same, having means to maintain the tamping means at any elevation to which it is moved by the explosive being tamped, comprising a friction pawl, means for avoiding friction 30 between the cross-head and the tamping means when the tamping means has been thrown out of operation, comprising a cylinder and piston connection between the cross-head and the tamping means, compressed air connections for forcing the piston forwardly in the cylinder, and means for disconnecting the piston rod from the tamping means and holding the latter stationary when the latter is not operating, and 35 means coöperating with the cross-head for releasing the friction pawl and the bracket engaging pawl, comprising an air cylinder, a knocker connected thereto, a catch for engaging the knocker, a rotary valve adapted to be moved by the knocker and compressed air connections through the valve and to the said pawl releasing devices. 40 45 50

39. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, means for 55 avoiding friction between the cross-head and the tamping means when the tamping means has been thrown out of operation comprising a cylinder and piston connection between the cross-head and the tamping means, and 60 means for disconnecting the piston rod from the tamping means and holding the latter stationary when the latter is not operating, and means coöperating with the cross-head for releasing the friction pawl and the 65 bracket engaging pawl, comprising an air

cylinder, a knocker connected thereto, a catch for engaging the knocker, a rotary valve adapted to be moved by the knocker and compressed air connections through the valve and to the said pawl releasing devices. 70

40. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, means for avoiding friction between the cross-head and the tamping means when the tamping means has been thrown out of operation, comprising 75 a cylinder and piston connection between the cross-head and the tamping means, compressed air connections for forcing the piston forwardly in the cylinder, and means for disconnecting the piston rod from the tamping means and holding the latter stationary when the latter is not operating, and means coöperating with the cross-head 80 for releasing the friction pawl and the bracket engaging pawl, comprising an air cylinder, a knocker connected thereto, a catch for engaging the knocker, a rotary valve adapted to be moved by the knocker and compressed air connections through the valve and to the said pawl releasing devices. 85 90 95

41. In a cartridge loading machine, tamping means, a cross-head adapted to carry the same, having means to maintain the tamping means at any elevation to which it is moved by the explosive being tamped, comprising a friction pawl, means for avoiding friction between the cross head and the tamping means when the tamping means has been thrown out of operation comprising 100 a cylinder and piston connection between the cross-head and the tamping means, and means for disconnecting the piston rod from the tamping means and holding the latter stationary when the latter is not operating, comprising a bracket on the tamping 105 means, a dogging pin thereon for engaging the piston rod and a pawl for engaging said bracket, and means coöperating with the cross-head for releasing the friction pawl and the bracket engaging pawl, comprising 110 an air cylinder, a knocker connected thereto, a catch for engaging the knocker, a rotary valve adapted to be moved by the knocker and compressed air connections through the valve and to the said pawl releasing devices. 115 120

42. In a cartridge loading machine, tamping means, a cross-head adapted to carry the same, having means to maintain the tamping means at any elevation to which it is moved by the explosive being tamped, comprising a friction pawl, means for avoiding friction between the cross-head and the tamping means when the tamping means has been thrown out of operation, comprising a cylinder and piston connection between the 125 130

cross-head and the tamping means, compressed air connections for forcing the piston forwardly in the cylinder, and means for disconnecting the piston rod from the tamping means, and holding the latter stationary when the latter is not operating, comprising a bracket on the tamping means, a dogging pin thereon for engaging the piston rod and a pawl for engaging said bracket, and means coöperating with the cross-head for releasing the friction pawl and the bracket engaging pawl, comprising an air cylinder, a knocker connected thereto, a catch for engaging the knocker, a rotary valve adapted to be moved by the knocker and compressed air connections through the valve and to the said pawl releasing devices.

43. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, means for avoiding friction between the cross-head and the tamping means when the tamping means has been thrown out of operation, comprising a cylinder and piston connection between the cross-head and the tamping means, and means for disconnecting the piston rod from the tamping means and holding the latter stationary when the latter is not operating, comprising a bracket on the tamping means, a dogging pin thereon for engaging the piston rod and a pawl for engaging said bracket, and means coöperating with the cross-head for releasing the friction pawl and the bracket engaging pawl, comprising an air cylinder, a knocker connected thereto, a catch for engaging the knocker, a rotary valve adapted to be moved by the knocker and compressed air connections through the valve and to the said pawl releasing devices.

44. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, means for avoiding friction between the cross-head and the tamping means when the tamping means has been thrown out of operation, comprising a cylinder and piston connection between the cross-head and the tamping means, and means for disconnecting the piston rod from the tamping means and holding the latter stationary when the latter is not operating, comprising a bracket on the tamping means, a dogging pin thereon for engaging the piston rod and a pawl for engaging said bracket, and means coöperating with the cross-head for releasing the friction pawl and the bracket engaging pawl, comprising an air cylinder, a knocker connected thereto, a catch for engaging the knocker, a rotary valve adapted to be moved by the knocker and compressed air connections through the valve and to the said pawl releasing devices.

45. In a cartridge loading machine, tamping means, a cross-head adapted to carry the same, having means to maintain the tamping means at any elevation to which it is moved by the explosive being tamped, comprising a friction pawl, a pawl releasing shaft on which it is pivoted, means for avoiding friction between the cross-head and the tamping means when the tamping means has been thrown out of operation, comprising a cylinder and piston connection between the cross-head and the tamping means and compressed air connections for forcing the piston forwardly in the cylinder, said cylinder having means for producing a reduced pressure on the other side of the piston from the portion containing the compressed air.

46. In a cartridge loading machine, tamping means, a cross-head adapted to carry the same, and means for avoiding friction between the cross-head and the tamping means when the tamping means has been thrown out of operation, comprising a cylinder and piston connection between the cross-head and the tamping means and compressed air connections for forcing the piston forwardly in the cylinder, said cylinder having means for producing a reduced pressure on the other side of the piston from the portion containing the compressed air, comprising means to permit air to readily escape therefrom but to retard the entry of air into the same.

In testimony that I claim the foregoing I have hereunto set my hand.

CLARENCE EUGENE JACK.
